UNITED STATES PATENT OFFICE.

ROBERT NELSON FULLER, OF ARLINGTON, TEXAS.

RESILIENT WHEEL.

1,231,872.

Specification of Letters Patent.

Patented July 3, 1917.

Application filed November 2, 1916. Serial No. 129,158.

To all whom it may concern:

Be it known that I, ROBERT NELSON FULLER, a citizen of the United States, residing at Arlington, in the county of Tarrant, State of Texas, have invented a new and useful Resilient Wheel; and I do hereby declare the following to be a full, clear, and exact description of the invention, such as will enable others skilled in the art to 10 which it appertains to make and use the same.

This invention relates to an improved resilient wheel, and an object of the invention is to provide a device of this kind provided 15 with a plurality of heavy wire spokes, each consisting of two sections which are arranged tangentially and have their adjacent ends spaced and connected by coil springs, there being an elongated frame, 20 through the opposite ends of which the adjacent end portions of said sections slidably engage, thereby holding the sections alined.

A further object of the invention is to 25 provide collars on the adjacent end portions of the sections of each spoke, between which collars and the opposite inner ends of the frame coil springs are interposed, to further insure resiliency.

In practical fields, the details of construction may necessitate alterations falling 30 within the scope of what is claimed.

The invention comprises further features and combination of parts, as hereinafter set forth, shown in the drawings, and claimed.

25 In the drawings:—

Figure 1 is a view in side elevation of the improved wheel constructed in accordance with the invention.

Fig. 2 is a sectional view on line 2—2 of 40 Fig. 1.

Fig. 3 is a detail perspective view of the two sections of one of the spokes, showing the connecting slideable frame and coil springs.

45 Referring more especially to the drawings, 1 designates the usual felly provided with a conventional form of tire 2 and 3 denotes a hub having adjacent its opposite end annular flanges 4. The inner ends of 50 the spokes 5 of the wheel pass through these flanges 4 and have their ends riveted, as shown at 6. The spokes 5 have their outer ends threaded at 7 into the rim 1. Each spoke consists of two sections, the inner section 8 (which is connected to the 55 hub) and the outer section 9, (which is con-

nected to the rim 1). The adjacent ends of the two sections 8 and 9 slidably engage through the openings 10 and 11 of the opposite ends of an elongated frame 12. The 60 opposite ends of each frame 12 have the thick parts 13, so that the end portions of the sections will slide through the openings 10 and 11 without binding. The adjacent extremities of the two sections of each spoke 65 are connected by a coil spring 14. The adjacent end portions of the two sections of each spoke are provided with collars 15, between which and the inner faces of the end parts 13 of the frame, coil springs 16 are 70 interposed. It is to be noted that as the hub of the wheel vibrates or moves downwardly, the springs adjacent the upper portion of the felly will stretch, that is the springs 14, while the springs 16 will compress. The openings 10 and 11 in the opposite ends of each frame are of such sizes and proportions that the sections of each spoke will move freely, without binding, especially with regard to the spokes adjacent 75 the horizontal diameter of the wheel.

The invention having been set forth, what is claimed as new and useful, is:

1. In a spring wheel, a hub having annular flanges adjacent its opposite ends, a 85 felly, a plurality of heavy wire spokes having their inner ends connected to such flanges and converging toward each other and having their outer ends connected to the felly, thereby preventing dishing of the 90 wheel, each spoke consisting of two alined sections arranged tangentially to the hub, a rectangular frame, through the inner and outer ends of which the adjacent end portions of the sections slidably pass, the inner 95 end of the frame being thicker than the outer end to insure a substantial guide for one of the sections of the spoke, a tension spring connecting the adjacent ends of the two sections, a collar on each of the adjacent ends of the two sections, and compression springs on the two sections, one between each collar and an end wall of said frame.

2. In a resilient wheel, the combination of 105 the hub and felly, of a plurality of heavy wire spokes connected between the hub and the felly, each spoke comprising two alined sections tangentially disposed with reference to the hub, a tension spring connecting the adjacent ends of the two sections, a collar attached to each of the adjacent ends of the 110

two sections, a rectangular frame in surrounding relation to the tension spring and to the collars and having oppositely disposed eyes through which the two sections 5 of the spoke pass and compression springs encircling the two sections and interposing between the collars and the opposite walls of the rectangular frame, the opposite end walls of said rectangular frame being of 10 different thicknesses and the frame itself

having a tapering outline adjacent to the thick wall to prevent its interference with the frames of adjacent spokes.

In testimony whereof I have signed my name to this specification in the presence of 15 two subscribing witnesses.

ROBERT NELSON FULLER.
